BRACKET FOR HOLDING FISHING RODS

George B. Hoagland, 2104 Wichert Drive,
Cuyahoga Falls, Ohio

Filed Nov. 6, 1959, Ser. No. 58,228

Term of patent 14 years
(Cl. D33—3)

FIG. 1

FIG. 2

FIG. 3

FIG. 4

Fig. 1 is a front perspective view taken from the top and left end of a bracket for holding fishing rods embodying my new design;

Fig. 2 is a rear elevational view thereof on a slightly reduced scale;

Fig. 3 is a top plan view thereof as shown in Fig. 2, the bottom being substantially plain; and,

Fig. 4 is a right end elevational view thereof as shown in Fig. 2.

I claim:

The ornamental design for a bracket for holding fishing rods, substantially as shown and described.
